TONGUE AND LIP HOLDING DEVICE FOR AIDING CORRECT ENGLISH SPEECH

Yun Gee, New York, N. Y.

Application November 23, 1949, Serial No. 6,210

Term of patent 14 years

(Cl. D83—1)

To all whom it may concern:

Be it known that I, Yun Gee, a citizen of the United States, residing at New York, in the county and State of New York, have invented a new, original, and ornamental Design for a Tongue and Lip Holding Device for Aiding Correct English Speech, of which the following is a specification, reference being had to the accompanying drawing, forming part thereof.

Fig. 1 is a plan view of a tongue and lip holding device for aiding correct English speech embodying my new design; and

Fig. 2 is an edge view thereof.

I claim:

The ornamental design for a tongue and lip holding device for aiding correct English speech, substantially as shown.

YUN GEE.
